UNITED STATES PATENT OFFICE

ERICH R. ZADEMACH, OF ELIZABETH, NEW JERSEY, ASSIGNOR, BY MESNE ASSIGNMENTS, TO HOBART MANUFACTURING COMPANY, OF TROY, OHIO, A CORPORATION OF OHIO

WASHING MACHINE

Application filed March 5, 1932, Serial No. 92,387. Renewed January 2, 1932.

This invention relates to washing machines and aims particularly to provide a simple, inexpensive, compact, and effective dish washing machine for household use.

5 Objects of the invention are to provide, in such a machine, a convenient and inexpensive casing, a compact pump and sump unit, a combined filling, drain, and overflow pipe which automatically drains the pump casing 10 as well as the sump, and a distributor which is freely removable to facilitate cleaning.

Other objects and advantages of the invention are hereinafter set forth in connection with a detailed description of the machine embodying the various features of the invention which are shown in the accompanying drawings in which

Fig. 1 is a front view of the machine resting upon a drain board attached to a sink, 20 and showing a hose connection between the standpipe of the machine and an ordinary faucet;

Fig. 2 is an end view of the machine showing the machine placed directly in a sink 25 (shown in vertical section) with the standpipe in draining position;

Fig. 3 is an enlarged end elevation of the machine with the movable top section in closed position, sectioned on the line 3—3 of 30 Fig. 5;

Fig. 4 is an enlarged front elevation of the machine, sectioned on line 4—4 of Fig. 3;

Fig. 5 is a plan view of the machine sectioned on the line 5—5 of Fig. 3, showing 35 the strainer broken away, and including a phantom view of the tank;

Fig. 6 is an enlarged fragmentary horizontal section on the line 6—6 of Fig. 3;

Fig. 7 is an enlarged vertical section on 40 the sump and pump unit taken on the line 7—7 of Fig. 4, showing the distributor mounting in axial section;

Fig. 8 is a section of the sump and pump unit taken on the line 8—8 of Fig. 3; and

45 Fig. 9 is a section of the sump and pump unit on the lines 9—9 of Figs. 4, 5 and 8, showing the pump involute drain channel.

The dish washing machine illustrated is 50 of the type in which soapy water or other washing medium is drawn from a sump or

reservoir 1 by a motor-driven pump 2 and forced into a distributor 3, such as a rotary wash arm, from which it is projected against the dishes. The water which has passed over the dishes drains back into the sump so that it may be used repeatedly.

The casing of the machine is made entirely of sheet metal. It may consist of only four parts, each of which may be drawn or otherwise formed from a single piece of sheet metal. These parts include a supporting shell 10, a shallow tank 11, a fixed cover section 12 and a movable cover section 13. The supporting shell 10 contains the motor, pump, and sump, and may be made of small area owing to the fact that the pump and sump are combined in a single unit, as hereinafter explained. The small area of the supporting section facilitates placing the machine on a sink, as shown in Fig. 2, or on a wash tub, without interference with the faucets. The shallow tank 11 is secured to and rests on the upper edge of the supporting shell 10 and is of larger area than the shell. The bottom of the tank slopes inwardly to an opening 14 leading to the sump 1. The fixed cover section 12 and the movable cover section or door 13 enclose a washing chamber above the tank 11. The fixed section 12 has a cylindrically curved top 15 and flat ends 16 consisting of sectors of a circle only slightly greater than quadrants and low projections 17 extending toward the front of the tank. The end walls may be provided with external strengthening pieces 18. The movable section has also a cylindrically curved top 19 and flat ends 20 consisting of sectors of a circle slightly greater than quadrants. The movable section is pivoted to the fixed section at 21 so that it may be turned within the fixed section. Because of the fact that the end walls of the fixed and movable sections are of approximate quadrant shape, this exposes one-half of the top and ends of the tank 3, thus facilitating the placing of a rack 22 of dishes 23 or other articles on rails 24 provided for its support and the removal of the rack therefrom.

A clearance is provided between the ends 100 and tops of the fixed and movable sections 12,

- 13 to permit the escape of steam during the washing operation, thus avoiding danger of scalding the user by a sudden escape of steam when the door is opened. Leakage of water between the fixed and movable sections is prevented by an inturned flange 25 at the front edge of the top and sides of the fixed section and outwardly projecting ribs 26 near the back edge of the top and sides of the movable section. Leakage under the lower edge of the movable section is prevented by an inturned flange 27 at the front edge of the tank 11 and by baffles 28 projecting inwardly from the forward projections 17 of the end walls of the fixed section just under the lower edge of the end walls of the movable section.
- The sump 1 and pump 2 are combined in a single unit 30 (which may most desirably consist of a single casting as shown) forming a box-like reservoir which constitutes the sump 1 and the involute casing 31 of the pump 2 which is of the centrifugal type. The unit 30 has an external flange 32 at its upper edge, which is secured to the bottom of the tank 11 about the edge of the opening 14. A removable strainer 33 may be seated on the inner part of the flange 32. One wall 34 of the pump casing 31 forms part of one of the side walls of the sump and contains an opening 35 for the passage of liquid from the sump to the pump casing. The discharge neck or conduit 36 of the pump casing rises within the sump 1 and extends into the tank 11 through the opening 14. The impeller 37 of the pump is driven by an electric motor 38 mounted on a strip 39 extending across the inturned lower edge 40 of the supporting shell 10. The impeller shaft 41 passes through two stuffing boxes 42 in the outer wall 43 of the pump casing 31. A drain passage 44 in the wall 43 diverts any liquid which may leak through the inner stuffing box and prevents it from entering a bearing 45 in which the shaft 41 is supported.
- To provide for draining both the sump and the pump casing, the unit 30 has at one of its lower edges a hollow cylindrical extension or sleeve 46 which communicates with the sump through an opening 47. A drain channel 48 formed in the bottom of the unit 30 extends from the lowest point of the pump casing 31 to the sleeve 46 opening into the sleeve just below the opening 47.
- A combined filling, overflow, and drain pipe 50 extends through the sleeve 46 and is turnable therein. The inner end of the pipe 50 is closed by a plug 52 while the outer end of the pipe extends through a hole 53 in the shell 10 and is turned nearly at right angles to the rest of the pipe to form an open standpipe 54. Lengthwise movement of the pipe 50 is prevented by a fixed collar 55 and a spring-pressed collar 56 engaging opposite ends of the sleeve 46 (see Fig. 4). The spring-pressed collar 56 serves also to create fric-

tion which holds the pipe 50 and its standpipe 54 in any position into which they may be turned. Turning of the pipe 50 is positively limited by the engagement of stops 57, 58 on a collar 59 with a strip 60 which extends across the bottom of the shell 10. The stops are placed so that the pipe 50 may be turned between a position in which its standpipe 54 is turned vertically upward (as shown in Figs. 1 and 4 and in dotted lines in Fig. 75 3), and a position in which the standpipe 54 is inclined rearwardly and slightly downward (as shown in Fig. 2 and in dot and dash lines in Fig. 3).

The portion of the pipe 50 within the sleeve 46 contains a lateral port 62 which registers with the drain opening 47 of the sump in all positions of the pipe 50 and with the drain channel 48 from the pump casing only when the standpipe is turned down (see Figs. 3, 4, 5, 85 and Figs. 7 and 9 which show the position of the port 62 when the standpipe is turned down to the position indicated by dot and dash lines in Fig. 3).

When the standpipe 54 is turned upward, 90 the sump 1 and tank 11 may be filled through the pipe 50, for example, by means of a rubber hose, as shown in Fig. 1. Alternatively, the machine may be filled by raising the door 13 and pouring water directly into the tank 95 11. In either case the standpipe 54 acts as an overflow pipe determining the level of the liquid in the tank 11 and preventing the liquid from rising high enough to interfere with the rotary distributor 3, hereinafter described. 100 The standpipe 54 is maintained in upright position during the operation of the machine, thus preventing the escape of water from the sump, while at the same time the wall of the pipe 50 prevents any water from passing out 105 of the pump casing through the drain channel 48.

When the standpipe 54 is inclined downwardly, both the sump and the pump casing are completely drained through the pipe 50 and the standpipe. This not only prevents stagnant water from collecting in the pump casing, but is of particular advantage in a machine intended for household use, since the soapy water used in washing the dishes may be quickly and completely withdrawn from the machine to make ready for the introduction of clean water for rinsing.

The plug 52 and the collars 55, 56 and 59 are detachable from the pipe 50 so that the pipe may be reversed to extend through an opening 53' in the shell 10 placing the standpipe 54 at the left-hand end of the machine, as shown in Fig. 2.

The rotary distributor 3 is of the type customarily known as a rotary wash arm. It has a hub 70 and radial arms 71 provided with upwardly directed nozzles 72 some of which are inclined so that the distributor is rotated by reaction. The hub 70 is mounted on a

hollow pin 73 which fits within and rests on the upper end of the discharge conduit 36 of the pump casing. The pin is provided with lateral outlet openings 74 whose combined area is greater than that of the cross-section of the discharge neck 36 so that the liquid which is forced through the pin does not tend to raise it from the discharge neck. In consequence the pin 73 may be made freely removable from the discharge neck without any attachment thereto. This facilitates removing the pin for cleaning.

The upper end of the hub 70 of the distributor is open and provided with an internal flange 75 which supports the distributor by resting on an external flange 76 near the upper end of the pin 73. The lower portion 77 of the hub 70 has a running fit over a rib 78 on the pin.

20 The opening at the upper end of the hub 70 is of such size that, when any fluid is passing through it, fluid pressure within the distributor does not tend to blow it off the pin. Consequently, the distributor may be made 25 freely removable from the pin without any attachment whatever, so that it need merely be lifted off for cleaning. When fluid is forced into the distributor, it raises the distributor slightly until a thin film of water 30 flows out between the flanges 75 and 76. The distributor then "floats" on this film of water so that it rotates easily and wear on the flanges 75 and 76 is avoided.

The operation of the machine will, it is 35 believed, be readily apparent from the above description. In the use of the machine it is desirable, after inserting a rack of dishes through the door 13, to fill the machine with hot soapy water and operate it for a sufficient 40 time to cleanse the dishes, and then to drain off this water, refill the machine with clean hot water, and operate it again for a few moments to rinse the dishes.

Claims to certain important features of the 45 machine which has been described have been divided out of this application under requirement of the Patent Office and form the subject-matter of my divisional applications, 50 Serial Nos. 205,857, filed July 8, 1927, and 205,858, filed July 8, 1927.

What is claimed is:

1. In a washing machine, a casing enclosing a washing chamber and comprising a fixed 55 section having a curved top and flat approximately quadrant-shaped end walls, a movable casing pivoted to the fixed casing and having a curved top and approximately quadrant-shaped end walls spaced inwardly 60 from the fixed end walls and overlapping the edges of the same when the movable section is in closed position, inward projections on the fixed end walls, and outward projections on the movable end walls forming a tortuous 65 path between the overlapping portions of the

end walls adapted to permit the escape of steam and obstruct the passage of water.

2. A washing machine having a casing comprising a shallow tank, a fixed section having a curved top and approximately 70 quadrant-shaped end walls and having an inwardly projecting flange along the front edge of its top and its end walls, and a movable section pivoted to the fixed section and having a cylindrical top and approximately 75 quadrant-shaped end walls spaced inwardly from those of the fixed section and having an outwardly projecting rib extending along the rear portion of its top and end walls.

3. In a washing machine, a casing consisting of a shallow tank, a fixed section having a curved top and end walls comprising quadrants rising from the rear half of the side edges of the tank and low projections rising from the front portion of the side edges of 85 the tank, a movable section having a curved top and approximately quadrant-shaped end walls whose lower edges fit within the forward projections of the fixed end walls, and baffles projecting inwardly from said projections below the lower edge of the end walls 90 of the movable section.

4. In a washing machine, a casing comprising a shallow tank, a fixed section having a curved top and flat end walls forming more 95 than one-quarter and less than one-half of a hollow cylinder, a movable section pivoted to turn within the fixed section and having a curved top and flat end walls constituting more than one-quarter and less than one-half 100 of a hollow cylinder so that the fixed and movable sections overlap when the movable casing is in closed position, and means for preventing the escape of liquid between the overlapping portions of the curved tops of 105 the fixed and movable sections, comprising a ridge formed on each curved top and projecting towards the other curved top, at least one of said ridges being spaced from the edge of the top from which it projects. 110

In testimony whereof I have hereunto set my hand.

ERICH R. ZADEMACH.
